UNITED STATES PATENT OFFICE

LOUIS M. FABBRO, OF CLEVELAND, OHIO, ASSIGNOR, BY DIRECT AND MESNE ASSIGNMENTS, OF FORTY-FIVE PER CENT TO ANNA M. FABBRO, AND FORTY PER CENT TO E. C. BALZHISER, BOTH OF CLEVELAND, OHIO, AND FIFTEEN PER CENT TO CHARLES DI LORENZIO

VAPORIZER AND SUPERCHARGER FOR INTERNAL COMBUSTION ENGINES

Application filed May 21, 1930. Serial No. 454,390.

This invention relates to a vaporizer and supercharger for internal combustion engines, the general object of the invention being to provide means for heating and thoroughly vaporizing the explosive mixture as it passes from the carburetors to the cylinders so as to greatly increase the efficiency of the engine by increasing the combustibility of the charge, increasing the miles per gallon, preventing overheating and carbonization of the engine and otherwise securing the maximum efficiency with the minimum amount of fuel.

The present invention is an improvement over that forming the subject matter of an application filed by me on October 11, 1929, Serial No. 399,029.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation of a motor, showing the invention in use thereon.

Figure 2 is a longitudinal sectional view through the device.

Figure 3 is a transverse sectional view thereof.

Figure 4 is a view of the inner face of the front end member of the device.

Figure 5 is a similar view of the rear end member.

Figure 6 is a sectional detail view of the thermostatic means.

Figure 7 is a sectional view through the T coupling in the exhaust pipe.

In these drawings, the numeral 1 indicates the outer cylinder which is preferably fastened to the top of the motor M by the straps 2, the ends of the cylinder being closed by the end pieces 3 which are bolted or otherwise fastened to the cylinder, each end piece being formed with an annular shoulder 4 on its

inner face, these shoulders forming seats for the inner cylinder 5 which is of considerably less diameter than the outer cylinder so that the cylinders form an annular chamber 6 between them. Each end member is formed with a frusto-conical recess 7 in its inner face, these recesses forming continuations of the space formed by the inner cylinder and the front end member is formed with a passage 8 which communicates with the recess 7 of said end member and which is connected by the pipe 9 with a carburetor 10. A similar passage 11 is formed in the rear end member and this passage is connected by a pipe 12 with the intake manifold 13 of the motor. A passage 14 is formed in each of the end members 3 and these passages communicate with the annular space 6 and a pipe 15 connects the passage 14 in the front end member with a T coupling 16 which is connected with the exhaust manifold 17 and the exhaust pipe 18 of the motor. A pipe 19 connects the passage 14 in the rear end member with the exhaust pipe 18.

A shaft 20 passes through the front end member and has its rear end fitting in a bearing recess 21 formed in the hub of a spider 22 located in the rear end of the inner cylinder 5, a small tube 23 extending through the rear member to the recess so that lubricant placed in a cup 24 on the outer end of the tube will pass to the bearing recess and thus lubricate the parts. The front end of the shaft is provided with a pulley 25 over which a belt 26 passes, this belt also passing over a pulley 27 on the shaft of the fan 28 of the motor. Thus the shaft 20 will be driven by the motor.

Spiders 29 are carried by the shaft 20 and are located within the inner cylinder 5 and a cylinder 30 of foraminous material is attached to said spiders so that this cylinder will rotate with the shaft. A fan 31 is attached to the shaft 20 and has its periphery connected with the cylinder 30, this fan being arranged at approximately the center of the inner cylinder 5. A spiral 32 is arranged at each side of the fan and is connected with the shaft and the cylinder 30, this spiral being also formed of foraminous material. The baffles 33, also formed of foraminous

material, are connected with the shaft and cylinder 30 and are arranged between the convolutions of the spirals. Thus the cylinder 30, the two spirals 32, the baffles 33 and the fan 31 all rotate within the inner cylinder 5.

From the foregoing it will be seen that the mixture from the carburetor enters the front recess 7 through the passage 8 and then enters the inner cylinder 5, where it is acted on by the spirals, the baffles and the fan so that the mixture leaves the cylinder 5 in the form of a mist and this mist passes through the pipe 12 into the inlet manifold 13, from which it passes to the cylinders of the motor. The exhaust gases pass through the pipe 12 into the front passage 14 and after circulating around the inner cylinder in the space 6, the exhaust gases pass through the rear passage 14 into pipe 19, from which they pass into the exhaust pipe. Thus these hot gases will highly heat the explosive mixture passing through the inner cylinder 5 so that they are vaporized at the same time they are being acted on by the spirals, baffles and fan 31, so that the mixture enters the cylinders in a highly combustible state.

A valve 34 is arranged to control the flow of exhaust gases into the pipe 15 and the arm of this valve is connected by a link 35 with an arm 36 which is pivoted in the casing 37 of a thermostatic device, the inner end of the arm having a toothed segment 38 thereon which engages a gear 39 rotatably arranged in the casing 37 and which is acted on by a toothed part 40 attached to the upper end of a thermostatic member 41, the lower end of which is connected to the lower end of a tube 42 into which the member 41 passes, this tube extending into the space 6 between the inner and outer cylinders, as shown in Figures 1 and 3. Thus the thermostatic device is acted on by the hot exhaust gases passing through said space and the movement of the thermostatic member will control the damper or valve 34 and thus the flow of exhaust gases through the space 6 will be automatically controlled. As shown, when the thermostatic member is in neutral position, the damper will close the exhaust pipe 18 so that all the exhaust gases will pass through the pipe 15 into the space 6, but when the thermostatic member is fully expanded, the damper will close the communication between the pipe 15 and the coupling 16 so that none of the gases will pass through the device. The gear 39 also operates the finger 43 pivoted in the casing 37 and operating over the scale 42 for indicating the temperature of the exhaust gases passing through the device.

Thus I have provided means for thoroughly vaporizing and commingling the explosive mixture as it passes from the carburetor to the motor, the mixture being heated by the exhaust gases from the motor and the tempera-

ture to which the mixture is heated being automatically controlled by the thermostatic device. This invention will produce a highly explosive mixture so that the engine will start quickly and the mileage is increased and overheating and carbonization of the engine is prevented and the greatest amount of efficiency secured with the minimum amount of fuel.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A mixing device for an explosive mixture, comprising inner and outer cylinders spaced apart to form an annular chamber, end plates closing the ends of the cylinders, each plate being formed with a central recess forming a continuation of the inner cylinder and a pair of passages, one passage being in communication with the annular chamber and the other with the recess, whereby exhaust gases can be passed through the annular chamber and explosive mixture through the inner cylinder, a cylindrical screen in the inner cylinder, a shaft passing through one of the end plates, bearing means for the other end of the shaft arranged in the inner cylinder, a fan connected with the shaft and with the cylindrical screen, baffles of foraminous material connected with the shaft and cylindrical screen, spirals of foraminous material connected with the shaft and with the cylindrical screen and means for rotating the shaft.

In testimony whereof I affix my signature.

LOUIS M. FABBRO.
